United States Patent Office.

GEORGE HEATH, OF LITTLE FALLS, NEW YORK.

Letters Patent No. 66,151; dated June 25, 1867.

IMPROVED CANAL LOCK.

The Schedule referred to in these Letters Patent and making part of the same.

TO ALL WHOM IT MAY CONCERN:

Be it known that I, GEORGE HEATH, of Little Falls, in the county of Herkimer, and State of New York, have invented a new and useful improvement in Canal Locks.

The nature of my invention consists in passing the water in the lock-chamber from the upper level through valves or openings in front of the gates, instead of passing it through valves or openings in the gate itself, as is usual, or through chambers or passages in the sides of the locks, as is sometimes done; and I do hereby declare that the following is a full, clear, and exact description of said invention, reference being had to the accompanying drawing, giving a perspective view of the improvement, one of the walls of the lock being removed.

A is the lock-wall; B is the breast-wall; C is the gate-chamber; D is the gate; E is the gate-platform; F F are the valves; G is the chamber below the platform E and connecting with the lock-chamber. The lock may be of any ordinary form, and of any proper new form, and the size or material is not important, and the improvement may be readily added to any lock now in use. In the ordinary lock, the part under the platform of the upper gate and up to the breast-wall is filled in with masonry, timber, or other material. In my improved lock this part is left open from the breast-wall to the lock-chamber. Over this place extends the gate-platform suitably supported and properly planked. In this platform at suitable points, and in suitable numbers, are placed the valves F F for filling the lock-chamber from above. The platform is at such distance below the breast-wall B that the valves when raised will not interfere with the passing boats, or with the operating of the lock-gate.

In the ordinary lock, as stated, the lock is usually filled through valves in the gates. The fall of the water through these valves into the lock below causes great commotion in the water in the lock and drives about the boat in the lock in a manner to do serious injury to the lock, as well as the boat, if not guarded against. To prevent such injury, it is necessary to fasten the boat by a stout line before letting in the water, which should be tightened as the boat rises with the rising water. By my improvement the water from the upper level passes through the valves F F vertically into the chamber G under said valves, and at some distance in front of the lock-chamber and of the boat, and commingling with the waters of the lock, the waters in the lock rise gently and without ebullition or agitation sufficient to disturb the boat resting therein. Where the water is let in through chambers at the side of the lock, instead of through valves in the gates, as is sometimes done, such chambers weaken the lock-walls and the rush of waters through them operates injuriously on the masonry, and it is with difficulty they are kept water-tight, and it is also with difficulty that repairs are made. In my improvement the valves or the whole platform may readily be taken up and repaired. With this improvement the tumble-gate may be used, but it does not prevent the use of the ordinary swinging gate, when it is desired.

In my improvement as ordinarily constructed with the tumble-gate, the valves are operated by levers all on one side of the lock, but any other mode that will effect the purpose will be sufficient.

Having thus described my invention, what I claim as new therein, and desire to secure by Letters Patent, is—
The mode, substantially as herein described, of filling canal locks.
